UNITED STATES PATENT OFFICE.

DAWID SUCHOSTAUER, OF LONDON, ENGLAND.

ELECTRIC TRACTION ON THE SURFACE-CONTACT SYSTEM.

No. 913,782.

Specification of Letters Patent.

Patented March 2, 1909.

Application filed March 5, 1908. Serial No. 419,359.

To all whom it may concern:

Be it known that I, DAWID SUCHOSTAUER, a subject of the Emperor of Austria-Hungary, residing at London, England, have invented certain new and useful Improvements in Electric Traction on the Surface-Contact System, and of which the following is a specification.

This invention relates to improvements in the surface contact system of electric traction for vehicles running on rails, by which the necessary insulated conductors and studs or switch mechanisms can be built in sections or self-contained units, each complete in itself, all ready to be placed in position, and connected with one another by tensile screw couplings interacting with the conductor sections themselves, so that the system may be applied to existing tramways or railways without disturbing the rails of the permanent way, or necessitating the complete reconstruction thereof.

The invention further relates to the construction hereafter described of shoe or skate carried by the car to contact with the studs on the permanent way, magnetically operate the switch mechanism, and collect the current.

According to this invention I construct a number of similar boxes or troughs of insulating material of suitable length, of which the sides or the tops, or both, are removable. The ends of the boxes are perforated to allow the passage of an electric conductor which extends axially throughout each box, and projects through the perforated ends. The screw-threaded ends of each conductor interact with tensile screw couplings in the form of internally screw-threaded sleeves, and each conductor is further provided within the box with nuts interacting with the ends of the box, so that the conductors of adjoining boxes may be mechanically and electrically connected with each other and the adjoining boxes may also be mechanically connected by one and the same series of tensile couplings interacting with conductor sections themselves, and the ends of the boxes brought together firmly by the same action. Washers of indiarubber or other suitable material are placed between the abutting ends of the boxes, or a short section of boxing or troughing may receive the adjacent ends, and the joint be made water-tight by filling with a suitable plastic cement. When complete,

the conductor forms an insulated line wire, and is connected in any well known way to a source of electrical energy.

The exterior or upper surfaces of some or all of the boxes carry metallic contact studs at such a level that a skate, shoe, or contact maker carried upon a vehicle traveling upon the rails, will rub upon and make electrical contact with the said studs. For a double line of rails there may be two lines of contact studs placed to suit vehicles on the two lines of rails, in which case the boxes are laid between the two lines of rails. The longitudinal spacing of the studs is so related to the length of the skates or collectors upon the vehicles, that contact is not broken with one stud until it has been made with at least one other. The contact studs are normally disconnected from the conductor or line wire in the boxing beneath them, but each is provided with a contact surface, so disposed that a conducting rocker or switch arm connected to the line wire and free to turn about it, contacts with the said line wire upon turning. Or the switch arm may be carried by the stud, and turn upon a pivot to make contact with the line wire. In either case the rocker or switch arm is made of magnetic material, such as wrought iron, or is connected to a piece of such material, and the vehicle is furnished with or carries a magnet, so disposed that when the magnet is over a stud, and the skate and collector in contact therewith, the switch arm or rocker is magnetically moved into the position of contact, and the vehicle thus supplied with electrical energy. On the passing away of the magnet, the switch arm, acted upon by gravity, resumes its normal position, in which the contact stud is disconnected from the line wire.

The car or other vehicle intended to travel upon a tramway or railway equipped with the surface contact system herein described, is provided with a skate, so arranged as to overhang the line of studs and to make contact with them by its lower surface. This contacting surface is provided with a series of rollers which make actual contact with the studs.

The under-surface of the shoe also carries suitable means, preferably squeegees, for cleaning the surfaces of the studs, and may also carry forward and rearward inclined plates for removing obstructions from the path of the skate.

The rollers and the frame, or sole plate from which they are carried, form part of a magnetic circuit excited by an electro-magnet or magnets, and so disposed that the 5 magnetic field produced, effects the required movement of the rockers or switch arms and the connection of the line wire to the contact studs, and through them to the shoe or skate, and so to the electrical equipment of 10 the car.

The accompanying drawings show forms of construction suitable for application to a railway, which embody the essential features of my invention. For tramway use 15 the form of construction is modified to suit the permanent way and pavement structure.

Figure 1 is a vertical longitudinal section through a length and a portion of an adjacent length, of boxing or troughing containing 20 a length of line wire, and showing a joint, with a single stud carried by the top cover, and a rocker or switch arm attached to the line wire. Fig. 2 is a vertical cross section of a boxing arranged to carry two 25 sets of studs for a double line of rails. Fig. 3 is a sectional elevation showing an example where the switch arms are carried by the contact stud. Fig. 4 is a vertical cross section of a shoe or skate and magnet carried 30 by the car, and a stud and rocker making contact. Fig. 5 is a sectional elevation showing the contact-making part of the 35 skate, the contacting rollers, a squeegee, and a guard plate.

Referring now particularly to Figs. 1 and 2, the trough or boxing 1 is shown in this case of a rectangular cross section, with a removable top or cover 2, but I may utilize other sections and make one side, or one 40 side and the top, removable, as may be most convenient for application, or for economical manufacture. The material of the boxing may be earthenware, slate, glass, wood, or any other suitable insulating material, or 45 sheet or cast metal suitably lined and bushed. The conductor or line wire 3 having screwed ends, is threaded through the box 1 by way of holes formed in its ends, and the screwed end of one conductor 3 of one box is connected to the screwed end of the other conductor of the next box as shown at Fig. 1, by means of a screwed ferrule or sleeve 4, and nuts 5 are provided, which may be caused to bear up against the interior ends 50 of the box. 6 is a washer of india-rubber or other suitable material, located between the adjacent ends of the boxes 1 so as to be compressed thereby, and to make a water-tight joint. I may, at the joint between two boxes, 55 employ a larger or U-shaped piece or socket 7 (Figs. 1 and 2), to receive the ends of the boxes, and then I may run in cement or luting to further secure and complete the joint. In the construction shown at Fig. 1, the line 60 wire within a box carries for each contact

stud a saddle or ring 8 clamped to the wire 3, and to this saddle are pivoted arms 9 formed with a head 10 to compose the rocker or switch arm, the arms and head of this switch arm being composed of magnetic 70 metal. The head 10 of the switch arm may carry a plate of carbon or other suitable conducting material 11 to contact with the underside of the contact stud 12 mounted in the lid or top of the box 1. The head 10 of 75 the switch arm is made with downwardly extending wings 13, which pass astride the conductor 3 and limit the normal position of the switch arm. It will be understood that the box may be made of a length to 80 carry any suitable number of contact studs 12 and to contain their corresponding switch arms, and the latter, when attracted by the magnetization of the contact stud 12, turn in a vertical plane about the pivot on the 85 saddle 8, so that when moved upwards, the contact surface block or plate 11 strikes the under-surface of the stud 12. Normally the switch arm remains in the horizontal position shown at Fig. 1 under the action of 90 gravity. The contact stud 12 is of iron. The magnet carried by the car is so disposed as to produce an attraction between the contact stud 12 and the head 10 of the switch arm, in virtue of which the switch arm rises 95 into the contact-making position, and the contact stud 12 is thereby electrically connected to the line wire, permitting a current to pass to the collector or skate on the car; on the removal of the magnet carried by the 100 car, the switch arm falls back to the position shown at Fig. 1 and leaves the contact stud 12 disconnected. At Fig. 2 the rockers or switch arms are shown at right angles to the line wire, and in Fig. 1 parallel to it; the 105 arrangement shown at Fig. 2, is, however, most suitable for a double line of contact studs 12 corresponding to a double line of rails. In the construction illustrated by way of example, the arms 9 of the rockers are 110 pivoted upon opposite sides of the line wire 3 to a saddle 8, and extend at right angles to the line wire. Any desirable means may be employed to regulate the normal position of the said switch arms, the means shown in 115 the illustration consisting in the arms 9 being formed with tail parts 14 which bear up against the line wire 3 and prevent any further descent of the switch arms.

In some cases as before explained, the 120 switch arm may be carried by the contact stud instead of by the line wire, and an illustration of such a construction is shown at Fig. 3, where a tubular plunger 15 of iron is fitted, free to move vertically upon a stem 125 or spindle 16 of non-magnetic metal, the said spindle extending downward from a contact stud 12. The lower end of the spindle 16 is screwed into a retaining ring 17 on the interior of the top of the box 1, and this 130

ring is slotted and carries two arms 9 on pivots 9^x. The arms 9 carry heads 10, and the tails of the arms 9 extend into a groove or recess in the tubular plunger 15. The 5 arms 9 and the heads 10 are in electrical connection with the retaining ring 17. With this construction, when the contact stud 12 becomes magnetized, the tubular plunger 15 will be drawn upward and the arms 9 10 caused to descend, until their heads 10 contact with the line wire. The essential feature of this part of my invention is, that each length of boxing with its conductor, studs and switches, may be fitted up and 15 brought complete to the place where it is to be fixed, and may be then jointed up with the minimum of interference to the existing permanent way and traffic on the line.

The skate or collector which is carried by 20 the car to contact with the studs and magnetically operate the switch mechanism, is constructed as shown at Figs. 4 and 5, where 18 is an electro-magnet—19 being the winding thereof—carried from some part 20 of 25 the car, so that a pole of a magnet 18 overhangs the line of contact studs 12 on the surface of the box 1. The outer pole face of the magnet 18 is fitted with side plates 21, slotted as at 22, Fig. 5, to carry the necks of 30 a succession of small rollers 23. These rollers make contact with the upper surfaces of the contact studs 12, and act as current collectors for the electrical equipment of the car, it being understood that the length of 35 the skate and the distance apart of the studs are so regulated, that the skate rollers do not leave one contact stud before contacting with the next one. When over the contact studs, the rollers will be magnetically 40 attracted onto the stud heads, and so make the firmer electrical contact, while yielding easily to any small obstacle encountered. The skate is fitted with a squeegee 24 of 45 india-rubber or other suitable material, and also carries a guard plate 25 inclined toward the direction of motion. The electro-magnet may be excited by a single or double coil or winding 19 as shown, and when in operation, the current employed for exciting the 50 magnet is derived from the line wire. The boxes may be arranged as indicated at Fig. 4, or they may be constructed so as to be laid level with the surface of the road, and they may be located centrally of the way between 55 two pairs of rails, or they may only carry a single line of contact studs and then may be located adjacent to a line of rails, while a similar series of a single line contact studs in such boxes may be arranged adjacent to 60 the other pair of rails. Upon a vehicle being about to start, the shoe may be temporarily magnetized through some convenient source of electricity, and then upon the vehicle moving so that the shoe is 65 brought into contact with the first contact

stud of the permanent way, the magnetism of the shoe will be affected from the current derived from the line wire.

What I claim as my invention and desire to secure by patent is:—

1. In electric traction on the surface contact system for vehicles running on rails, the combination with a magnetized collector, carried by the car, of a number of lengths of box-like structures placed end to end in the permanent way, each constituting a self-contained unit, and each including a closed box of insulating material, an electric conductor in the form of a corresponding length of line wire extending lengthwise through said box and having screw-threaded ends, and nuts upon said ends within the box in contact with the box ends, tensile screw couplings by which the conductors of adjoining units are mechanically and electrically connected endwise and the adjoining boxes are mechanically connected endwise; metallic contact studs on the upper surface of the units, and magnetically operated switches to connect said contact studs with said electric conductors during the contact of said collector with said studs.

2. In electric traction on the surface contact system for vehicles running on rails; the combination with a magnetized collector carried by the car; of a number of lengths of box-like structures placed end to end in the permanent way, each consisting of a trough-shaped box, a cover to close the open part of same, an electric conductor extending lengthwise through said box and projecting through the ends of same, metallic contact studs on the upper surface of said box, and magnetically operated pivoted switch arms within said box to connect said contact studs with said electric conductor during the contacts of said collector with said studs, screw-threads formed on the ends of said electric conductor, an internally screwed sleeve to connect the screwed ends of the conductor of one box to the ends of the conductors of adjacent boxes, and a resilient washer placed around each of said sleeves and located between the adjacent ends of each two boxes to form a water-tight joint.

3. In electric traction on the surface contact system for vehicles running on rails; the combination with a magnetized collector carried by the car; of a number of lengths of box-like structures placed end to end in the permanent way, each consisting of a trough-shaped box, a cover to close the open part of same, an electric conductor extending lengthwise through said box and projecting through the ends of same, metallic contact studs on the upper surface of said box, a saddle fixed on said electric conductor within said box, arms pivoted on said saddle, and a contact head carried at the free ends of said arms to contact with the under-surface of a con-

tact stud when magnetically attracted there-
to by the passage of the magnetized collector
over the contact stud, screw-threads formed
on the ends of said electric conductor, an in-
5 ternally screwed sleeve to connect the screwed
ends of the conductor of one box to the ends
of the conductors of adjacent boxes, and a
resilient washer placed around each of said
sleeves and located between the adjacent
10 ends of each two boxes to form a water-
tight joint.

4. In electric traction on the surface con-
tact system for vehicles running on rails;
the combination with a magnetized collector
15 carried by the car; of a number of lengths
of box-like structures, each open at the top
and placed end to end in the permanent way,
a cover to close the open part of each box,
contact studs on the outer surface of said
20 cover, and shanks from said contact studs
extending to the inner face of said cover, an
electric conductor extending lengthwise and
axially through each box and passing
25 through the end walls thereof, means for
mechanically and electrically connecting the
ends of the conductors of the adjacent boxes
and for forming a water-tight joint, and
magnetically operated pivoted switch arms
30 within said box to connect said contact studs
with said electric conductor during the con-
tact of said collector with said studs.

5. In electric traction on the surface con-
tact system for vehicles running on rails; a
35 current collector consisting of the combina-
tion of an electro magnet carried from the
car, means for electrically exciting said
magnet, side plates on the end of the pole of
said magnet overhanging the contact studs
40 of the permanent way, said plates having
vertical slots, and a number of small mag-
netic metal rollers journaled in said slots of
said side plates so as to be capable of ver-
tical movement when said rollers contact
45 with said contact studs for magnetically op-
erating electric switches.

6. In electric traction on the surface con-

tact system for vehicles running on rails; a
current collector consisting of the combina-
tion of an electro magnet carried from the
car, means for electrically exciting said mag-
net, side plates on the end of the pole of said
50 magnet overhanging the contact studs of the
permanent way, said plates having vertical
slots, a number of small magnetic metal
rollers journaled in said slots of said side
55 plates so as to be capable of vertical move-
ment when said rollers contact with said
contact studs for magnetically operating
electric switches, a squeegee mounted at each
60 end of said collector, and an inclined guard
plate at each end of said collector.

7. In electric traction on the surface con-
tact system for vehicles running on rails;
the combination with a current collector
composed of an electro-magnet carried from
65 the car, means for electrically exciting said
magnet, side plates on the end of the pole of
said magnet overhanging the contact studs
of the permanent way, and a number of
small magnetic metal rollers carried between
70 said side plates to contact with the contact
studs of the permanent way; of a number
of lengths of box-like structures placed end
to end in the permanent way, each consist-
75 ing of a trough-shaped box, a cover to close
the open part of same, an electric conductor
extending lengthwise through said box, me-
tallic contact studs on the upper surface of
80 said box, and magnetically operated switches
to connect said contact studs with said elec-
tric conductor during the contact of said
collector with said studs, and means for me-
chanically and electrically connecting the
85 ends of the conductors of the adjacent box-
like structures.

In witness whereof I have hereunto set
my hand in the presence of two witnesses.

DAWID SUCHOSTAUER.
